as per

UNITED STATES PATENT OFFICE.

DAVID F. HAYNES, OF BALTIMORE, MARYLAND.

DESIGN FOR A EWER OR JUG.

SPECIFICATION forming part of Design No. 21,306, dated January 19, 1892.

Application filed December 26, 1891. Serial No. 416,243. Term of patent 3½ years.

To all whom it may concern:

Be it known that I, DAVID F. HAYNES, a citizen of the United States, residing at Baltimore, Maryland, have invented and produced a new and original Design for a Ewer or Jug, of which the following is a specification, reference being had to the accompanying drawings, forming a part hereof.

Referring to the annexed drawings, Figure 1 is an exterior side elevation of the ewer, and Fig. 2 a top view of the same.

I describe the ewer or jug as follows: Its body A is a frustum of a circular spindle, terminating at the upper end in a cylinder, with a bead *a* at its edge.

Near the lower end of the body is a circular band *b*, and leading from this band in a downward direction are small channels *c* at equal distances apart, which terminate in a circumferential groove *d*.

Leading from the band *b* in an upward direction are beads *e*, which divide the circum-

ference of the body into four spaces *f*, devoid of ornamentation in relief, and four intermediate narrow spaces *g*, having a Hindoo-²⁵ strip pattern in relief.

The lip *B*, which projects above the edge of the body, is ornamented by a grotesque human head or face having a beard resembling a leaf, which extends down the body.

The handle *C* begins slightly below the center of the body and terminates at a band *h* on the cylinder portion of the body, at which point it is bifurcated or branched and clasps the neck. The handle has a grotesque head ³⁰ ³⁵ somewhat resembling that of a lion and is otherwise ornamented with foliage.

I claim as my invention—

The design for a ewer or jug, as herein shown and described.

DAVID F. HAYNES.
